UNITED STATES PATENT OFFICE.

JOHN H. BURKHOLDER, OF ASHLAND, OHIO.

DESIGN FOR A LIFTING-JACK STANDARD.

44,837.

Specification for Design.

Patented Nov. 4, 1913.

Application filed December 8, 1911. Serial No. 664,666. Term of patent 7 years.

To all whom it may concern:

Be it known that I, JOHN H. BURKHOLDER, a citizen of the United States, residing at Ashland, county of Ashland, and State of Ohio, have invented a new, original, and ornamental Design for a Lifting-Jack Standard, of which the following is a specification, reference being had to the accompanying drawing, forming part thereof.

The single figure represents a perspective view of a lifting jack standard.

I claim:

The ornamental design for a lifting jack standard, substantially as shown.

JOHN H. BURKHOLDER.

Witnesses:

F. N. PATTERSON,
BESS WELTY.
